UNITED STATES PATENT OFFICE.

LEWIS A. DARLING, OF PHILADELPHIA, PENNSYLVANIA, ASSIGNOR TO ELECTRIC SERVICE SUPPLIES COMPANY, OF PHILADELPHIA, PENNSYLVANIA, A CORPORATION OF PENNSYLVANIA.

TURBINE AND TURBINE-WHEEL.

1,401,321.

Specification of Letters Patent. Patented Dec. 27, 1921.

Application filed March 4, 1919. Serial No. 280,562.

To all whom it may concern:

Be it known that I, LEWIS A. DARLING, a citizen of the United States, and a resident of Philadelphia, in the county of Philadelphia and State of Pennsylvania, have invented certain new and useful Improvements in Turbines and Turbine-Wheels, of which the following is a specification, reference being had to the accompanying drawings.

My invention relates to turbines and turbine wheels, and especially to turbines of the radial flow type. It is concerned both with the mounting and arrangement of the turbine buckets or blades and the construction of the turbine wheel or rotor in general, and also with the direction of the motive fluid to secure the desired action on the rotor.

As regards buckets and wheel and fluid directing means, the main objects of the invention are stability and permanence of the structure; simplicity of construction and facility of assemblage; and general economy of manufacture; as regards the action of the motive fluid on the rotor, reduction of the rotor speed necessary to operating efficiency by fractional abstraction of the kinetic energy of the fluid. These features are of special advantage in the case of very small turbines, as will readily be understood.

In the drawings, Figure I, is a side view of an elastic fluid turbine wheel constructed in accordance with my invention and of motive fluid directing means associated with it, said directing means and the adjacent portion of the wheel being in section.

Fig. II, is an edge view of the wheel and of the adjacent fluid directing means, the last mentioned part being in section.

Fig. III, shows the wheel in section at the line III—III, of Fig. I.

Fig. IV, is an enlarged fragmentary view similar to Fig. I, but taken from the other side of the wheel; it shows in section a fluid directing means which in Fig. I, appears in dotted lines.

Fig. V, is a view of the fluid directing device shown at the left of the wheel buckets in Fig. IV, as seen from the right of Fig. IV.

Fig. VI, is a view of a modified form of fluid directing device corresponding to that shown adjacent the wheel periphery in Figs. I and II, on a larger scale.

Fig. VII, shows a section through the last mentioned device on the line VII—VII, of Fig. VI.

Fig. VIII, is a view of the same device in section at the line VIII—VIII, of Fig. VII.

Fig. IX, is a perspective view of a bucket on an enlarged scale, showing one form of anti-turning engagement lug on its end surface.

Fig. X, is a fragmentary sectional view illustrating a modified construction of the turbine wheel.

Fig. XI, is a similar view of a further modification.

Referring first to Figs. I, II, and III, it will be seen that the turbine wheel has a plurality of peripheral bucket passes formed, as shown by rows of buckets 10 and 11, mounted endwise against opposite sides of the wheel body 12, so as to project laterally or overhang with reference to the adjacent portion of the wheel structure. As shown, the buckets 11, are made larger than the buckets 10, so as to handle properly a larger volume of motive fluid, so that the two passes may act properly when the fluid traverses them in succession.

The motive fluid is first directed against one side of the bucket pass 10, by a nozzle 15, adjacent the buckets; and as it issues from the other side of the pass, it is received by a re-directing element 16, and turned through an angle of about 180° and redirected back into the bucket pass 11, issuing at the side of the buckets at which it first entered the pass 10. The recess or cavity of the member 16, is "stepped" in a plurality of cylindrical surfaces 17, which are at appropriate angles to one another for acting properly on the streams of fluid issuing from the curved wheel periphery at various points.

From Figs. I, IV, and V, it will be seen that the fluid issuing from the bucket pass 11, as just described, may be received by an additional directing element 18, and by it turned through an angle of approximately 180° and re-directed back against the side of the bucket pass 11, whence it just issued, so as to traverse this same pass once more. This last directing member 18, consists, as shown in Figs. IV and V, of a part having in one side a substantially U-shaped channel, inclined with reference to its curved face ad-

adjacent the buckets, and a cover plate 19, secured to one side of this part.

As shown, the initial one of the aforesaid fluid-directing devices—the discharge nozzle 15,—is arranged inside the overhanging bucket pass 10: the first re-directing element 16, is arranged adjacent the wheel periphery; and the other re-directing element 18, is arranged inside of the overhanging bucket pass 11. The re-directing guide element 16, has a bracket 20, (see Fig. II) for securing it to the turbine casing or other structure (not shown), and the element 18, is secured to an appropriate flange or other portion 21, of such structure (see Fig. V),—the plate 19, lying adjacent the wheel body or web 12. It will be seen that by this arrangement, the kinetic energy of the motive fluid is abstracted fractionally,—that is to say, in successive steps,—as the fluid makes its successive traverses through the wheel buckets.

The directing device 26, shown in Figs. VI, VII, and VIII, corresponds in function and action to the device 16, of Figs. I and III, but is adapted to re-direct the motive fluid more efficiently by avoiding mingling and interference of the currents of fluid entering and leaving the device. As shown, the device 26, has a main body part 27, similar to the one part which forms the entire device 16. In the walls of the recess or cavity of this part 27, at the boundaries between the steps of its inner surface, are inclined grooves 28, and in these grooves are mounted appropriately shaped metal plates 29, which divide the recess into a plurality of pockets. In each of these pockets is mounted a block 30, which, in combination with its other walls, forms a U-shaped pass 31, and separates the entering and leaving streams of motive fluid. As shown, the blocks 30, are placed to one side of the centers of the pockets, so that the U-shaped passes 31, enlarge slightly toward their exits. It will be observed, moreover, that the plates 29, act to separate the U-shaped passes and obviate interference and consequent eddies of the streams of motive fluid which might otherwise result from the angle between the median planes of adjacent passes.

I will now describe in detail the construction of the turbine wheel.

As will be seen from Figs. I and II, the main body of the wheel comprises a central hub 32, with a conical axial opening and a shouldered peripheral flange 33, and a pair of metal plates 34, and 35, secured at opposite sides of this flange by rivets 36. As shown, these plates are dished, and their portions surrounding the central dished portions lie in contact and are secured together by spot welding. The bucket-carrying outer edge or rim portions 38, 38, of the plates 34, and 35, are, as shown, offset or "joggled"

away from one another at 39, 39, to afford an intermediate space. As the buckets 10 and 11, are secured to the rim portions 38, 38, in exactly the same manner, it will suffice to describe in detail the securing of the 70 buckets 10.

From Figs. I and II, it will be seen that the bucket-mounting rim element of each half of the wheel comprises not only the main rim portion or member 38, just referred to, but also a supplemental rim member 40, in the form of a flat ring lying against the main rim member. The buckets 10, it will be seen, have at their ends which are seated against the main rim member 38, engagement means adapted to coöperate with a correlative feature of said rim member to prevent turning of the buckets with reference thereto. As shown in Fig. IX, this engagement means may have the form of a lug 41, upstanding from the end surface of the bucket 10, and this lug 41, may have a rectangular shape for anti-turning engagement in an appropriately shaped aperture in the main rim member 38, to facilitate rapid assemblage, the sides of the lug 41, may be inclined or tapered. It will be understood, however, that a great variety of other shapes besides rectangular would enable the lug 41, to perform its anti-turning function.

On the other ends of the brackets 10, is a cover element 42, (shown in Fig. 1, as comprising a plurality of sections or segments) for securing the buckets endwise against the rim element 38, 40. Securing members 43, extend from cover to rim and secure these two mounting elements together independently of the buckets 10. As shown, in Figs. I, II, and IX, the buckets 10, have holes 44, extending length-wise through them and registering with corresponding holes in the members 38, 40, and 42, and the securing members 43, extend through all these parts and have heads 45, 46, engaging the members 40 and 42, having, indeed, the form of rivets.

It will be seen that the outer edges of the supplemental rim members 40, lie somewhat within those of the main rim members 38, and that against the shoulder so formed there lies a strip or band member 47, which not only covers the rivet heads 45, 45, and makes the periphery of the whole wheel perfectly even, but also positively spaces the main rim members 38, 38, apart outside the rivets 43, 43, and resists any tendency for the centrifugal force on the parts to bend said rim members 38, 38, inward toward one another. This member 47, may be secured to the adjacent edges of the rim members 38, 38, by brazed, fused, welded, or other similar joints, so as to make it virtually integral with them.

In Fig. X, I have shown a construction in

which supplemental rim members are dispensed with and a single set of rivets 50, employed to secure together the two members 51, 51, and the parts associated with each of them. The strip or band member 52, which spaces the rim members 51, 51, apart and resists deformation of them by centrifugal force lies directly against the middle portions of the rivets 50, and is 10 secured to said rim members 51, 51, by fillet-like fused joints 53, 53.

In Fig. XI, the outer edges of the rim members 54, 54, are bent over to form flanges 55, 55, that meet edgewise and so 15 perform the functions of the member 52, of Fig. X. Their edges may, if desired, be secured together by a fused joint.

In all three forms of wheel construction shown, therefore, the wheel rim as a whole 20 is inherently stable and balanced, substantially, against deformation by centrifugal force on the buckets, by virtue of the positive (and, as shown, integral) spacing means between the outer edges of the disk 25 rims and the co-action therewith of the rivets.

Having thus described my invention, I claim:

1. In a turbine, the combination of a 30 wheel with a plurality of peripheral rows of radial-flow buckets, means for directing motive fluid against the buckets of one of said rows from one side thereof, means for re-directing the fluid issuing from said 35 buckets to strike the buckets of the other row, and means for again re-directing the fluid back through the buckets of the second row.

2. In a turbine, the combination of a 40 wheel with a plurality of peripheral radial flow bucket passes overhanging on opposite sides of the adjacent body portion; means for directing motive fluid against buckets of one of said passes from one side 45 thereof; means for redirecting the fluid issuing from said buckets back through the buckets of the other pass; and means for again re-directing the fluid back against the buckets of said latter pass.

50 3. In a turbine, the combination of a wheel with a plurality of peripheral radial flow bucket passes, the buckets projecting laterally or overhanging with reference to the adjacent portion of the wheel structure in one of said passes; means inside said 55 overhanging pass for directing motive fluid outward against its buckets; means adjacent the periphery of the wheel for re-directing the motive fluid inward to the buckets in the other pass and means for again 60 re-directing the fluid back through the buckets of latter pass.

4. In a turbine, the combination of a 65 wheel with a plurality of peripheral radial flow bucket passes overhanging on opposite

sides of the adjacent body portion; means inside one of said overhanging passes for directing motive fluid outward against its buckets; means adjacent the periphery of the wheel for re-directing the motive fluid inward to the buckets in the other pass; and means inside said latter pass for re-directing the motive fluid back against the buckets of said latter pass.

5. A turbine wheel comprising a hub, a 75 pair of disks or plates secured together and to said hub, the plates lying in contact near their peripheries and their outer edge or rim portions being joggled away from one another; a row of radial flow buckets arranged endwise against the rim portion of each plate; cover elements on the other ends of said buckets; and rivets extending through cover elements, buckets, and rim members and securing them together; the 80 separated joggled rim portions of said plates being positively spaced apart, at their outer edges, against deformation by centrifugal force.

6. A turbine wheel in accordance with 90 claim 5, in combination with a band between the rim members serving to space them apart and resist deformation of them by centrifugal force.

7. A turbine wheel comprising a pair of 95 disks or plates secured together and in contact near their peripheries, the outer edge or rim portions of said plates being joggled away from one another, but positively and integrally spaced apart at their outermost 100 edges against deformation by centrifugal force; rows of radial flow buckets arranged endwise against the rim portions of said plates; cover elements on the other ends of said buckets; and rivets extending through 105 cover elements, buckets, and rim members and holding them together; so that the wheel rim as a whole is inherently stable and balanced, substantially, against deformation by 110 centrifugal force on the buckets.

8. A turbine wheel comprising a pair of dished disks or plates secured together with a hub between their central dished portions and their surrounding portions in contact, the outer edge or rim portions of said plates 115 being joggled away from one another, but positively spaced apart at their outermost edges against deformation by centrifugal force; rows of radial flow buckets arranged endwise against the rim portions of said plates; cover elements on the other ends of said buckets; and rivets extending through cover elements, buckets, and rim members and holding them together; so that the wheel rim as a whole is inherently stable 120 and balanced, substantially, against deformation by centrifugal force on the buckets.

9. A turbine wheel comprising a pair of dished disks or plates secured together with a hub between their central dished portions 130

- and their surrounding portions in contact, the outer edge or rim portions of said plates being joggled away from one another, a row of radial flow buckets arranged endwise against the rim portion of each plate, cover elements on the other ends of said buckets, and rivets extending through cover elements, buckets, and plates with heads in the space between their rim portions.
- 10 10. A motive fluid re-directing device for use in connection with a wheel having two peripheral radial flow bucket passes, said device comprising a part with a step-bottomed recess and with inclined grooves in

the walls of said recess at the boundaries 15 between the steps, metal plates in said grooves dividing the recess into a plurality of pockets, and a block in each pocket forming, in combination with its other walls, a U-shaped pass lying at an angle to the wheel 20 periphery.

In testimony whereof I have hereunto signed my name at Philadelphia, Pennsylvania, this first day of March, 1919.

LEWIS A. DARLING.
